DESIGN FOR A DRESS ENSEMBLE

Albert Ruchman, New York, N. Y.

Application March 25, 1940, Serial No. 91,202

Term of patent 3½ years

To all whom it may concern:

Be it known that I, Albert Ruchman, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design;

Fig. 2 is a rear view of Fig. 1;

Fig. 3 is a fragmentary front view of the ensemble shown in Fig. 1 with the jacket unbuttoned;

Fig. 4 is a fragmentary front view of the dress member thereof.

The rear blouse portion of the dress member is conventionally plain.

I claim:

The ornamental design for a dress ensemble, substantially as shown and described.

ALBERT RUCHMAN.
